UNITED STATES PATENT OFFICE.

WALTER F. WHITON, OF BANGOR, MAINE.

SPOKE-SOCKET.

SPECIFICATION forming part of Letters Patent No. 339,721, dated April 13, 1886.

Application filed January 15, 1886. Serial No. 188,641. (No model.)

To all whom it may concern:

Be it known that I, WALTER F. WHITON, a citizen of the United States, residing at Bangor, in the county of Penobscot and State of Maine, have invented a new and useful Spoke Socket and Tenon; and I do hereby declare that the following is a full, clear, and exact description of the invention, which will enable others skilled in the art to which it applies to make and use the same.

My invention relates to an improved socket and tenon for the spokes of vehicle-wheels, and is illustrated in the accompanying drawings, in which—

15 Figure 1 is an isometric view of spoke-socket turned upward. Fig. 2 is a front elevation of the form of bolt shown in Figs. 3 and 4. Fig. 3 is a sectional view through the center of the spoke, showing all the parts in position. Fig. 4 is a longitudinal sectional view showing all the parts in position. Fig. 5 is a sectional view of a second form of my device through the center of the spoke, showing all the parts in position. Fig. 6 is a front elevation 20 of the form of bolt shown in Fig. 5. Fig. 7 is a sectional view of a third form of my device through the center of the spoke, showing all the parts in position. Fig. 8 is a front elevation of the form of bolt shown in Fig. 7.

25 30 Similar letters refer to corresponding parts throughout the several figures.

The object of my invention is to provide a device whereby the size of the mortises for the reception of the spokes in the felly of the wheel may be reduced to a minimum, the necessity of the shoulders commonly formed around such mortises obviated, the tenons wholly omitted from the exterior ends of the spokes, or, when not omitted, clasped, braced, 35 and supported in such a manner as to prevent their wearing and rattling in their sockets, and thus, speaking generally, to produce a stronger and better wheel.

In the construction shown in Figs. 1, 2, 3, 45 and 4, I provide a metallic socket, A, preferably of steel, consisting of the spoke-socket proper, a, rim or plate a', and hub a'', all being preferably formed integral. The part a is shaped to receive the tenon or point of the spoke S, and from and around its exterior surface, at or near its base, projects the rim or plate a', shaped to fit and bear upon the

inner edge of the felly F and lap over its sides, if desired. The under side of the base of the socket a may be convexed, to conform to the 55 curve of the inner edge of the felly, or may be slightly prolonged in its cylindrical shape below the bottom of the plate a', as shown in the figures above referred to. From the center of the under side of the base of the socket a, and 60 in the direction of its longitudinal axis, is projected the hub a'', of lesser diameter than the socket a, and preferably countersunk at its exterior end. The felly is correspondingly mortised to receive the hub a'', and when the 65 prolonged socket is used, to receive such prolongation also. The length of the hub a'' is not invariable; but I prefer to construct it of a length somewhat less than half the thickness of the felly. I further provide a metallic 70 bolt, B, fitting the hub a'', having a screw-threaded point, b, and a head, b', (preferably countersunk,) near the mid-length of its stem, and when countersunk adapted to fit a corresponding countersink in the exterior end of 75 the hub a''.

In operation the spoke-socket A is fitted upon the exterior end of the spoke S, or when the end of the spoke is tenoned, upon the tenon. The point b of the bolt B is introduced through 80 the bore of the hub a'' and screwed into the spoke S, which is bored to receive it until the head b' of the bolt rests upon the exterior end of the hub. The end of the spoke is thus drawn tightly against the bottom of the socket 85 a, and the spoke S, spoke-socket A, and bolt B are firmly held together, and the portion b'' of the bolt projecting above the bolt-head b' forms, essentially, a tenon to the spoke, or a continuation of the tenon, if the spoke be tenoned, 90 the felly being mortised to receive the part b'' of the bolt, and the hub a'' (and also the prolongation of the socket proper, a, when such prolongation is used) is then fitted upon the part b'' of the bolt, which part is preferably 95 formed of sufficient length just to fall short of reaching the outer surface of the felly, although, if desired, it may be made of some-what lesser length, in which case the mortises need not extend through the whole thickness 100 of the felly.

The form shown in Figs. 5 and 6 differs from that before described simply in forming an internal screw throughout the whole length of

the bore of the hub a'' , and a corresponding external screw, b''' , upon the stem of the bolt B, extending from immediately beneath the head b' for a distance substantially equal to the length of the bore of the hub, omitting the screw-threading beyond the point thus reached and leaving the round point b''' of the bolt smooth. In this form the bolt B screws into the hub a'' , as shown in Fig. 5, and not into the spoke, which is simply bored to receive the round point b''' of the bolt. The bolt still serves as a tenon to the spoke or as a continuation of the tenon when the spoke is tenoned, but ceases to draw and hold the external end of the spoke to the bottom of the socket a . A substitute for this form may be produced by forming the bolt and socket integral; but I should not consider it so desirable as that I have described, as it would possess less strength.

The form shown in Figs. 7 and 8 differs from that first described simply in the substitution of a common screw-bolt with common head, stem, and threaded point for the screw-bolt shown in Fig. 2. The spoke-socket used is that shown in Fig. 1, and the application of this form is shown in Fig. 7, (the screw-bolt itself being represented in Fig. 8,) the threaded point screwing into the spoke as in the first form, but the head of the screw, which is preferably countersunk, bearing upon a corresponding countersink in the outer edge of the felly instead of the hub. The spoke is held in the felly, substantially in the same way as by the form shown in Figs. 3 and 4, with the added advantage that when, owing to shrinkage or warping of the fellies, it becomes necessary to remove and reset the tires of the wheel, a slight turning of the screw-bolts, together with the usual kerfing at the junctures of the ends of the fellies, leaves the wheel ready for the reception of the tire after it has been upset in the usual way.

By means of my device I obviate the necessity of forming shoulders around the mortises of the felly, thus greatly simplifying the construction of the felly. I materially reduce the size of such mortises, (this becoming possible by reason of the metallic bolt B being substituted for the wooden tenon of the spoke, as commonly used.) When desired, I save the whole operation of tenoning the spoke, and I hold the spoke or spoke-tenon immovably in its socket, thus preventing rattling and wear

from the constant jar and strain unavoidable in the use of wheeled vehicles, and I produce 55 a stronger and neater wheel than those in common use.

I am aware that sockets for the spokes of wheels are not new, and therefore I do not claim a spoke-socket, broadly; nor do I claim, broadly, securing the spoke in the mortise of the felly by a screw-bolt, either with or without a spoke-socket; but

What I do claim, and desire to secure by Letters Patent, is—

1. In combination with the spoke and felly of a wheel, a spoke-socket having a rim or plate surrounding its outer periphery at or near its base, and a hub projecting from the under side of the base of the socket proper and in continuation thereof, and a bolt fitting said hub having a head near the mid-length of its stem, and a screw-threaded point, so that the portion of the stem above the head may project beyond the exterior end of the hub 75 when the parts are adjusted together and serve as a tenon or a continuation of the tenon of the spoke, substantially as described.

2. In combination with the spoke and felly of a wheel, a spoke-socket having a rim or 80 plate surrounding its outer periphery at or near its base, and a hub projecting from the under side of the base of the socket proper and in continuation thereof, said hub having an internal screw-threaded bore, and a bolt fitting the bore of said hub and having a round point, a head near its mid-length, and an external screw-thread below such head for a distance substantially equal to the length of the bore of said hub and corresponding to the internal thread of the bore thereof, substantially 90 as described.

3. In combination with the spoke and felly of a wheel, a spoke-socket having a rim or plate surrounding its outer periphery at or 95 near its base, and a hub projecting from the under side of the base of the socket proper and in continuation thereof, and a bolt having a countersunk head, a screw-threaded point engaging with the end of the spoke, and a smooth 100 stem fitting the bore of said hub, substantially as described.

WALTER F. WHITON.
